UNITED STATES PATENT OFFICE.

GEORGE P. WIGGINTON, OF KALAMAZOO, MICHIGAN, ASSIGNOR TO KALAMAZOO LOOSE LEAF BINDER COMPANY, OF KALAMAZOO, MICHIGAN.

INDEXED SHEET.

1,294,585.

Specification of Letters Patent. Patented Feb. 18, 1919.

Application filed February 2, 1917. Serial No. 146,104.

To all whom it may concern:

Be it known that I, GEORGE P. WIGGINTON, a citizen of the United States, residing at the city and county of Kalamazoo, State of Michigan, have invented certain new and useful Improvements in Indexed Sheets, of which the following is a specification.

This invention relates to improvements in indexed sheets.

10 My improved indexed sheet is especially designed by me for use in temporary binders or loose sheet holders of the type shown in Letters Patent No. 1,174,458, March 7, 1916, and is an improvement upon and an adaptation 15 of the sheets there disclosed. My improvements are, however, readily adapted and desirable for use in various other relations.

20 The main object of this invention is to provide an improved indexed sheet on which complete index indicia are displayed with a series or group of sheets arranged in an alined body or with a part of such sheets arranged in an offset relation.

25 Further objects, and objects relating to structural details, will definitely appear from the detailed description to follow.

30 I accomplish the objects of my invention by the devices and means described in the following specification. The invention is clearly defined and pointed out in the claims.

35 A structure which is a preferred embodiment of my invention is clearly illustrated in the accompanying drawing, forming a part of this specification, in which:

Figure I is a plan view of a group or series of my improved sheets disposed on a binder member with a part of the sheets in an offset relation.

40 Fig. II is a detail plan view similar to that of Fig. I with the sheets arranged in an alined body.

Fig. III is a plan view of one of the sheets.

45 Fig. IV is a reverse view of the sheet shown in Fig. III.

In the drawing similar reference characters refer to similar parts throughout the several views.

50 Referring to the drawing, 1 represents one of the members of a binder, such as shown in my patent referred to, 2 the binding strips, and 3 the removable binding posts. 4 represents a portion of a rack or holder for 55 the binder, such as shown in the Farron

Patent No. 1,197,468, Sept. 5, 1916, and 5 the sheet guide member of such a rack or holder. As these features form no part of my present invention I have not shown or described the same in detail herein. 60

The sheets 6 are provided with holes 7 adapted to receive the posts 3 and with spaced notches 8 at their binding edges adapted to receive the binding strips 2 and engage the guide 5 which facilitates the alining of the sheets. Sheets having these features are described and claimed in my said patent. 65

The sheets are arranged in series or groups, each sheet of the series being provided with index tabs 9. The tabs of the group or series of sheets are stepped and each group or series of sheets has a double set of tabs running from the side edges inwardly. Each set of tabs is provided with a double 70 set of index indicia 10. Each set of indicia in the embodiment illustrated constitutes the numerals 0-9, reading inwardly. Each tab is provided on both its sides with the indicia of the tabs preceding its tab position in the 75 series, so that the sheets may be reversed, without destroying the continuity of the sets of indicia, and the sets of indicia are disposed in relation to the notches 8 so that at least one complete set of indicia is displayed with the sheets alined or when a part 80 of the sheets are offset with the notches alined, as occurs when they are offset and engaged with the binding strips 2 or the guide 5. 85

This arrangement very greatly facilitates the manipulation of sheets in so-called machine posting, as it permits of selected groups of sheets being disposed in an offset relation without interfering with the running of the index thereof. It also permits all the sheets being shifted from one binder member or holder to another, as is illustrated and described in the said Farron patent, and facilitates the manipulation and use 90 of the sheets generally. 95

I have illustrated my invention in one form in which I have embodied the same for commercial use. I have not attempted to illustrate or describe certain modifications 100 which might be desirable to adapt my improvements to certain forms of binder devices or sheet holding means, as I believe the disclosure made will enable those skilled in the art to embody or adapt the same as may 110

be desired to meet the particular requirements.

Having thus described my invention, what I claim as new and desire to secure by Letters Patent, is:

1. A series of sheets provided with a plurality of open notches in their binding edges disposed so that the sheets may be arranged in an alined body or with a part thereof in an offset relation at either side with registering notches, the sheets being provided with a double set of stepped index tabs running from the side edges inwardly, each set of tabs being provided with a double set of indicia reading inwardly, each tab having on both sides thereof the indicia of the tabs preceding its tab position in the series so that the sheets may be reversed without destroying the continuity of the sets of indicia, said sets of indicia being disposed in relation to the said notches so that at least one complete set of index indicia is displayed with the sheets alined or with a part offset.
2. A series of sheets provided with a plurality of open notches in their binding edges disposed so that the sheets may be arranged in an alined body or with a part thereof in an offset relation at either side with registering notches, the sheets being provided with a double set of stepped index tabs running from the side edges inwardly, each set of tabs being provided with a double set of indicia reading inwardly, each tab having thereon the indicia of the tabs preceding its tab position in the series, said sets of indicia being disposed in relation to the said notches so that at least one complete set of index indicia is displayed with the sheets alined with a part offset.
3. A series of sheets provided with a plurality of open notches in their binding edges disposed so that the sheets may be arranged in an alined body or with part thereof in an offset relation at either side with registering notches, the sheets being provided with a set of index tabs having a double set of indicia, each tab being provided with the indicia of the tab preceding its tab position in the series, said sets of indicia being disposed in relation to the said notches so that there is at least one complete set of indicia displayed with the sheets alined or with a part offset.
4. A series of sheets provided with a plurality of open notches in their binding edges disposed so that the sheets may be arranged in an alined body or with part thereof in an offset relation at either side with registering notches, the sheets being provided with a double set of stepped index tabs running from the side edges inwardly, each set of tabs being provided with index indicia, each tab having on both sides thereof the indicia of the tabs preceding its tab position in the series so that the sheets may be reversed without destroying the continuity of the sets of indicia, said sets of indicia being disposed in relation to the said notches so that at least one complete set of index indicia is displayed with the sheets alined or with a part offset.
5. A series of sheets provided with a plurality of open notches in their binding edges disposed so that the sheets may be arranged in an offset relation at either side with registering notches, the sheets being provided with a double set of stepped index tabs running from the side edges inwardly, each set of tabs being provided with index indicia, each tab having thereon the indicia of the tabs preceding its tab position in the series, said sets of indicia being disposed in relation to the said notches so that there is at least one complete set of index indicia displayed with the sheets alined or with a part offset.
6. A series of sheets provided with alining means to facilitate the arranging of the sheets in an alined body or with a part thereof in an offset relation the sheets being provided with a double set of stepped index tabs running from the side edges inwardly, each set of tabs being provided with a double set of indicia reading inwardly, each tab having on both sides thereof the indicia of the tabs preceding its tab position in the series so that the sheets may be reversed without destroying the continuity of the sets of indicia, said sets of indicia being disposed in relation to the said alining means so that at least one complete set of index indicia is displayed with the sheets alined or with a part offset.
7. A series of sheets provided with alining means to facilitate the arranging of the sheets in an alined body or with a part thereof in an offset relation, the sheets being provided with a double set of stepped index tabs running from the side edges inwardly, each set of tabs being provided with a double set of indicia reading inwardly, each tab having thereon the indicia of the tabs preceding its tab position in the series, said sets of indicia being disposed in relation to the said alining means so that at least one complete set of index indicia is displayed with the sheets alined or with a part offset.
8. A series of sheets provided with alining means to facilitate the arranging of the sheets in an alined body or with a part thereof in an offset relation, the sheets being provided with sets of stepped index tabs provided with indicia, each tab of each set being provided with the indicia of the tabs preceding its tab position in the series, said sets of indicia being disposed in relation to the said alining means so that at least one complete set of index indicia is displayed with the sheets alined or with a part offset.
9. A series of sheets provided with a dou-

ble set of stepped index tabs running from the side edges inwardly, each set of tabs being provided with a double set of indicia reading inwardly, each tab having on both 5 sides thereof the indicia of the tabs preceding its tab position in the series so that the sheets may be reversed without destroying the continuity of the sets of indicia, said sets of indicia being disposed so that at least one 10 complete set of index indicia is displayed with the sheets alined or with a part offset. 10. A series of sheets provided with a double set of stepped index tabs running from the side edges inwardly, each set of tabs. 15 being provided with a double set of indicia reading inwardly, each tab having thereon the indicia of the tabs preceding its tab position in the series, said sets of indicia being disposed so that at least one complete set of

index indicia is displayed with the sheets 20 alined or with a part offset.

11. A series of sheets provided with a double set of stepped index tabs running from the side edges inwardly, each set of tabs being provided with indicia, each tab having 25 thereon the indicia of the tabs preceding its tab position in the series, said sets of indicia being disposed so that at least one complete set of indicia is displayed with the sheets alined or with a part offset. 30

In witness whereof, I have hereunto set my hand and seal in the presence of two witnesses.

GEORGE P. WIGGINTON. [L. s.]
